UNITED STATES PATENT OFFICE.

HENRY HORSEFIELD, OF PHILADELPHIA, PENNSYLVANIA, ASSIGNOR TO
WILLIAM O. ROWLAND AND ALBERT E. SCHMIDT, OF SAME PLACE.

DESIGN FOR A LACE CURTAIN.

SPECIFICATION forming part of Design No. 25,344, dated March 31, 1896.

Application filed August 14, 1894. Serial No. 520,309. Term of patent 7 years.

To all whom it may concern:

Be it known that I, HENRY HORSEFIELD, a subject of the Queen of Great Britain, residing in the city and county of Philadelphia, in 5 the State of Pennsylvania, have invented and produced a new and original Design for Lace Curtains, of which the following is a specification, reference being had to the accompanying drawing, which shows enough of a lace 10 curtain to fully illustrate my invention.

My design is drawn so as to show somewhat more than half of the lower border C and of the top border B of the curtain and some of the body ornamentalations E, which are the 15 same in all of the body. The line $x\ x$ is at about the middle of the curtain.

The chief feature of my design consists in a lace net, the ends of which are provided with a fringe, this net being provided with the 20 illustrated ornamentation and serving as a curtain.

A further feature is the scalloped edges D D'.

Referring to the pattern proper of the curtain, the lower border C consists of lyre-like 25 figures c combined with conventionalized flower-pieces c^2 between the figures c and somewhat similar pieces c' below these figures. The border F consists of a scalloped figure f with leaf-sprays and a flower f'.

The design at the upper border B consists of a flower and leaf design, as shown.

The body portion E of the curtain-net is ornamented with a flower and spray, as shown at e.

What I claim is—

The design for lace curtains; substantially as shown.

HENRY HORSEFIELD.
